UNITED STATES PATENT OFFICE

MARTIN FOEHNER, OF NEWARK, NEW JERSEY, ASSIGNOR TO HIMSELF AND
ALBERT FELLER, OF SAME PLACE.

IMPROVEMENT IN PADLOCKS.

Specification forming part of Letters Patent No. 173,932, dated February 22, 1876; application filed
January 31, 1876.

To all whom it may concern:

Be it known that I, MARTIN FOEHNER, of the city of Newark, in the county of Essex and State of New Jersey, have invented certain new and useful Improvements in Padlocks; and I do hereby declare that the following is a full, clear, and exact description thereof, which will enable others skilled in the art to which it appertains to make and use the same, reference being had to the accompanying drawings, and to the letters of reference marked thereon, which form a part of this specification.

This invention relates to that class of padlocks which are operated without tumblers or bolts, and in which the key-holes are hidden from sight.

The accompanying drawing fully illustrates the nature and character of my invention, in which—

Figure 1 is a cross-section of a padlock combining my improvements, and constructed in accordance with the principles embodied in my invention; and Fig. 2 is a cross-section of the key adapted to lock and unlock the same.

To enable those skilled in the art to which it appertains to make and use my lock, I will proceed to describe its construction and operation.

My invention consists in the peculiar form given to the lock, as well as in the manner of its construction and mode of operation.

The form herein shown, as will be observed, is that of an ordinary key, the handle of which constitutes the bow of the lock and the barrel the key-hole.

The padlock, as shown in Fig. 1 of the drawing, is locked, the key removed, and the key-

hole plugged up and also locked. In order to unlock it, I first unscrew the pin *a* by means of the key *A*, the handle of which is conformed and adapted to fit the head *a'* of said screw-pin, which head constitutes also a portion of the bit *b*, as shown and indicated in Fig. 1. When the pin *a* is unscrewed far enough to release the plug *C*, the latter is withdrawn and the key inserted in its place, with which another screw-pin, *c*, is unscrewed until the bow *D* is released, allowing it to be withdrawn, which completes the operation.

It may be observed that the several parts, especially the head *a'* of the screw-pin *a* and the plug *C*, should be fitted as neatly and snugly as possible, so that a person not informed would find it difficult, if not impossible, to discover its mode of operation.

The screw-pins *a* and *c* should also be fitted tightly, particularly the former, so that it cannot be turned by the thumb and fingers.

Having thus described my invention, what I claim as new, and desire to secure by Letters Patent of the United States, is—

A padlock of the form herein set forth and shown, and provided with the screw-pins *a* *c* and plug *C* and a key, *A*, adapted to lock and unlock the same, all being constructed, combined, and arranged to operate substantially as set forth and described.

In testimony that I claim the foregoing as my own I hereto affix my signature in presence of two witnesses.

MARTIN FOEHNER.
